(57) **CLAIM**

The ornamental design for a hose bag, as shown and described.

DESCRIPTION

FIG. 1 is a front, top, right-side perspective view of the hose bag of the present invention;

FIG. 2 is a front view of the hose bag design shown in FIG. 1;

FIG. 3 is a back view of the hose bag design shown in FIGS. 1 and 2;

FIG. 4 is a top view of the hose bag design shown in FIGS. 1-3; and,

FIG. 5 is a back, bottom, left-side view of the hose bag design shown in FIGS. 1-4, with a back, bottom, right-side perspective view being a mirror-image of FIG. 5.

The drawings show a hose bag. The broken lines shown represent stitching and form part of the claimed design. The zipper forms part of the claimed design.
